UNITED STATES PATENT OFFICE.

CHARLES HUGH DUFFY, OF MIAMI, FLORIDA.

CABLE-TOGGLE COUPLING.

Application filed March 2, 1928. Serial No. 258,619.

This invention relates to improvements in toggles for ropes, cables and the like.

In the use of simple toggles, the rope or cable which is looped around the center of the toggle receives the loop of the detachable rope or cable in such manner that the detachable loop of the rope or cable is constantly chafing and cutting into the rope or cable which is secured around the center of the toggle. To prevent this chafing and cutting of the ropes or cables, it is common practice to serve the said loops with a tough twine. This practice offers a temporary protection, but is by no means permanent, as upon the chafing and cutting of the serving, the loops become exposed at the contacting points of the two loops.

This invention has for its principal object, the construction of a toggle embodying a thimble element so arranged with relation to the toggle proper, as to insulate and separate the two loops of the ropes, cables or the like to effectually and permanently prevent the chafing or cutting of the said loops.

The invention is hereinafter more fully described in connection with the accompanying drawings. Objects of a more specific nature will become apparent in the description and the essential characteristics are summarized in the claims.

In the drawings:

Figure 1 is a front view of the coupling with cables connected thereto;

Figure 2 is a rear view of the same;

Figures 3 and 4 are front and rear views respectively of the coupling per se; and

Figure 5 is a central vertical section through the coupling with the positions of the cables indicated in broken lines.

The toggle is very simple in construction and consists of a casting or forging machined so as to form oppositely projecting members 10 of the toggle proper and central grooved part 11, a depending shield-like or thimble portion 12 and a transverse hole 13. The members 10 may be provided with arcuate grooves 14 on their undersides and the shield or thimble 12 is formed on its front face with a concave transverse surface 15. The detachable cable 16 is looped so as to receive the members 10 of the toggle proper and lie longitudinally of the structure in the grooves 14 and upon the surface 15 of the thimble portion 12; the terminal of the cable

being spliced and served above the toggle as indicated at 17. The members 10 and surface 15 thus act as a thimble for the terminal loop of the detachable cable 16.

The rear face of the shield 12 is formed with a grooved or recessed surface 18. The stationary cable 19 is passed over the grooved part 11, through hole 13 and over the recessed face 18, and lies transversely of the structure where the terminal thereof is spliced to the main strands at 23. The recessed face 18 is curved leading to the hole 13 so that the cable is not subjected to sharp corners but is subjected to easy bends. The loop of cable 16 also passes over rounded surfaces formed by the grooves 14 and concave surface 15 of the thimble portion 12 and in like manner is not subjected to sharp corners.

The toggle illustrated and described herein causes the strain on the cables to be properly distributed preventing undue distortion of the strands, and effectually separates or insulates the two loops 16 and 19, lying at right angles to each other while at the same time, the loop 16 is as quickly and readily detachable as in the use of simple toggles.

It will be noted that the embodiment of the thimble member, which connects with the toggle member proper at points on each side of the center of the latter stiffens and strengthens the toggle member proper and renders the same better capable of withstanding the sudden and heavy strains to which devices of this class are constantly subjected.

I claim:

1. A cable toggle comprising a unitary structure having oppositely projecting members adapted to receive transversely of the toggle the loop of a cable, a shield depending from said members and adapted to receive longitudinally of the toggle the loop of a cable, the said shield lying between the contiguous surfaces of the two loops of the cables to separate the same and prevent chafing of one loop on the other.

2. A cable toggle including oppositely projecting members adapted to receive transversely of the structure the loop of a cable, and adapted to receive longitudinally of the structure the loop of a cable, and a shield extending from the oppositely projecting members and adapted to lie between the con-

contiguous surfaces of the loops of the cables to separate the same and prevent chafing of one loop on the other.

3. A cable toggle coupling comprising a unitary structure provided with oppositely projecting members adapted to be received by the terminal loop of one cable, a part connecting said members and adapted to be received by terminal loop of another cable, a shield-like structure depending from said members and having a hole extending therethrough and transverse and longitudinal rounded surfaces for contacting respectively with said loops.
4. A cable toggle including oppositely projecting members adapted to receive transversely of the structure the loop of a cable, and a shield connecting the oppositely projecting members and adapted to straddle

the said loop of a cable, the said shield extending from the oppositely projecting members to receive in connection with said members, the loop of a cable longitudinally of the structure, the whole arranged in such manner that the said shield lies between the contiguous surfaces of the two loops of the cables to prevent chafing of one loop on the other.

5. A cable toggle adapted to receive the loops of two cables, one loop transversely of the structure and the other loop longitudinally of the structure so that the two loops lie at right angles to each other and means on the toggle for separating the contiguous surfaces of the two loops to prevent chafing of one loop on the other.

In testimony whereof I affix my signature.
CHARLES HUGH DUFFY.
